UNITED STATES PATENT OFFICE.

JOHN KASMEIER, OF BEEVILLE, TEXAS.

APPARATUS FOR DESTROYING WEEVILS.

1,232,323.

Specification of Letters Patent.

Patented July 3, 1917.

Application filed June 23, 1916. Serial No. 105,443.

To all whom it may concern:

Be it known that I, JOHN KASMEIER, a citizen of the United States, residing at Beeville, in the county of Bee and State of Texas, have invented a new and useful Apparatus for Destroying Weevils, of which the following is a specification.

This invention has reference to an apparatus for destroying weevils and moths, in festing corn, peas, hay, sweet potatoes, beans, and the like, when stored.

An object of the present invention is to provide a device for accomplishing this destruction of the weevils and the moths by the application of heat to the material or substances in which the weevils and moths are found.

Another object of this invention is to provide a crib or container for storing the corn, or the like, and to provide an air heater with an adjustable conducting pipe, which may be moved into various positions beneath the crib to distribute the heat at various sides or parts thereof, as is found desirable in heating the contents of the crib.

A further object of the invention is to provide an improved means for distributing the hot air throughout the body of the corn, or other substance placed in the crib, and to provide an improved controlling means for passing air up through the corn, and for retaining the heat in the crib when a desired temperature has been obtained.

Various other more or less important features of the invention will be specifically brought out in the following description of the present preferred embodiment of the invention, the same being illustrated in the accompanying drawings, wherein—

40 Figure 1 is a vertical central section through a heater constructed according to this invention, the dotted lines showing several positions into which the hot air conducting pipe may be adjusted.

45 Fig. 2 is a horizontal section, taken on the line 2—2 of Fig. 1, through the crib or container, and the central heat distributing tube, the view showing the perforated floor or bottom of the crib.

50 Fig. 3 is a horizontal sectional view, taken on the line 3—3 of Fig. 1, through the heating chamber, and showing the conducting pipe swung into various positions for dis-

tributing the heat to various sides of the crib.

Fig. 4 is a detail enlarged section, taken on the line 4—4 of Fig. 1, and showing the lower end of the thermometer tube with a thermometer suspended therein.

Fig. 5 is a detail enlarged view of the upper portion of the furnace hood or cap, and the upper end of the air flue, the view showing the adjustable hot air conducting pipe removed from the flue and a hot air diffusing disk mounted on the flue.

Referring to these drawings, wherein like parts are designated by similar numerals of reference throughout the several views, 10 designates the outer wall of the crib or container, which is adapted to receive the grain or vegetables to be heated. The crib is preferably of cylindrical form, is provided with a perforated bottom 11, and is supported upon an annular wall 12 arranged beneath the bottom 11 and forming thereunder a heating chamber. The lower portion of the crib is provided with an inwardly spaced annular wall 13 providing between the same and the outer wall 10 an annular air space, which opens downwardly through the bottom 11, into the heating chamber 12. The inner wall 13 is perforated, as shown, so that air passing upwardly from the heating chamber into the annular passage may pass through the perforations in the inner wall into the interior of the crib.

A heat distributing tube 14 rises from the central portion of the bottom 11 and extends upwardly substantially to the middle portion of the crib and has an imperforate top and a number of perforations in its side walls. The tube 14 opens downwardly through the bottom 11 into the heating chamber 12, so that heat in the heating chamber 12 may pass upwardly through the tube 14 and be distributed through the perforations therein into the grain or substance which surrounds the tube. A top wall or annular flange 15 joins the upper end of the inner wall 13 to the outer wall or casing 10. The top wall is imperforate, so as to deflect the heated air downwardly and prevent its free passage upwardly through the annular chamber. Thus, heat from the chamber 12 rises through the annular space or chamber of the crib and passes through

the perforated wall 13 into the grain, and the heat also passes centrally upward through the tube 14 and is distributed radially into the middle portion of the body 5 of grain.

The crib 10 is provided with a roof or top 16 of the usual form, and which has at its apex, or central portion, a ventilating tube 17, adapted to permit the passage of air 10 from the crib upwardly through the roof. A cap 18 is adjustably mounted upon the upper end of the ventilating tube 17, and, when open, as shown in Fig. 1, permits the free passage of the air upwardly through 15 the crib. At certain times, however, the cap 18 may be closed, so as to prevent a draft of air upwardly through the device.

The crib 10 is provided with a door 19, which may be hinged or otherwise suitably 20 mounted at one side of the crib, as shown in Figs. 1 and 2. An outside spout 20 with a valve 21 projects outwardly from one side of the crib adjacent the bottom thereof, and by means of which grain, or the like, may 25 be withdrawn from the crib. A second outlet spout 22 projects downwardly from the bottom 11 and is arranged inside of the heating chamber. This spout 22 has a valve 23 to control the passage of grain, or the like, downwardly through the spout.

For the purpose of heating air in the chamber 12, a furnace 24 adapted to burn coal, or any other fuel which is convenient and adaptable, is placed preferably in the 35 central portion of the cylindrical chamber 12. The furnace 24 has a central flue 25 extending upwardly therethrough, the flue having air inlet openings 26 at its bottom to receive air adapted for passage 40 upwardly through the tube 25, and to be heated by the surrounding fire in the furnace 24. The furnace 24 has a smoke pipe 27 extending from one side of the furnace, and through the wall 12, the pipe 27 opening 45 into a chimney 28, which preferably extends upwardly against the outside of the crib.

The central flue 25 is in the form of a cylindrical pipe which projects upwardly 50 through the furnace 24 and rises to a considerable extent beyond the same. A cap or hood 29 is placed over the upper end of the furnace, and the flue 25 projects upwardly through the central portion of the cap and 55 slightly beyond the same to provide a nipple, for a purpose which will hereinafter appear.

The cap 29 is supported on bracket arms 60, which are spaced about the upper end of the furnace 24, and which engage the hood 29 to hold it in slightly spaced relation about the furnace 24. Air, surrounding the furnace 24, when heated, passes upwardly into the cap or hood 29 and is confined therein, and caused to pass through a

plurality of air openings 31 formed in the flue 25 immediately beneath the top of the cap 29. Thus, the updraft of air through the flue 22 draws in the heated air from the cap 29, so as to discharge the heated air both from the flue and from the cap 70 upwardly through the nipple.

Detachably and adjustably mounted on the nipple or open upper end of the flue 25, is a conducting pipe 32, which lies substantially in a horizontal plane, and which is provided upon its inner end with a downwardly extending elbow adapted to fit over the upper end of the flue 25 and provide a pivotal support for the conducting pipe 32. 80 The outer free end of the conducting pipe 32 has an upturned elbow or portion to deliver the heated air from the flue 25 upwardly from the outer end of the conducting pipe.

As shown in dotted lines in Figs. 1 and 3, the conducting pipe 32 may be swung about the flue 25 into various positions, so as to dispose the outlet of the pipe 32 beneath the various portions of the crib 10, and thus 90 apply greater heat to such portions, as may be found desirable under various conditions of use. As shown particularly in Fig. 1, the conducting pipe 32 is adapted to be swung about the flue 25 into such positions 95 as to place the discharge end of the conducting pipe beneath the bottom 10 at points between the beams 33, so that the heat may pass upwardly through the openings in the bottom 11 and will not unduly heat the 100 beams, or be deflected thereby.

From Fig. 5, it will be noted that the conducting pipe 32 may be lifted upwardly from engagement with the flue 25, and be entirely detached. In lieu of the conducting 105 pipe, a spreading or distributing disk 34 may be placed over the upper end of the flue 25, and held in such position by means of spring fingers 35, as shown in Fig. 5. In this instance, the heat which rises 110 through the flue 25 strikes the lower face of the disk 34 and is deflected laterally in all directions beneath the disk 34, and is thus evenly distributed throughout the upper end of the heating chamber 12.

For the purpose of introducing grain into the crib 10, the top 16 thereof is provided at one side with a hinged door or closure 36, through which the grain, vegetables, or other materials may be introduced into the 120 crib for the purpose of filling the same. A guiding and protecting tube 37 is arranged centrally within the cylindrical crib 10, and is supported at its lower end on top of the distributing tube 14, the tube 37 extending 125 upwardly and preferably into the ventilating tube 17. The upper end of the tube 37 is open and is adapted to receive therein a thermometer 38, which is preferably suspended upon a cord 39 secured at its upper 130

end to a cross piece 40, to suspend the thermometer 38 in and adjacent to the bottom of the tube 37. The tube 37 permits the introduction of the thermometer 38 into the 5 middle portion of the body of grain, so that the temperature of the innermost part of the body of the substance may be easily ascertained. The tube 37 is preferably perforated, so that the heated air may pass freely 10 therethrough, and the correct registering of the heat may be effected.

In use, the material or substance is introduced through the hinged closure 36 into the crib 10. The material thus stored frequently 15 becomes infested with weevils, and the like, and to destroy the same, it is only necessary to fire the furnace 24 to heat air in the flue 25, and produce an upward suction of the air to raise the temperature of 20 the substance or material in the crib, and thus destroy the weevils. The draft of air passing up the flue 25 may be directed through the conducting tube 32 against the bottom 11 of the crib. The conducting tube 25 is turned about the upper end of the flue 25 to bring the tube into the desired adjusted position, so that certain parts of the material may be subjected to greater heating than other parts.

30 If it is desired to heat all parts of the bottom 11 simultaneously and evenly, the conducting tube 32 is removed from the flue 25, and disk 34 is placed upon the upper end of the flue, as shown in Fig. 5. The 35 spring fingers 35 bind about the upper edge of the flue and frictionally hold the disk 34 in spaced relation above the flue. In this instance, the heat is diffused by the disk into all parts or sides of the heating chamber 12.

40 The heated air passes upwardly through the perforations in the bottom 11, into the annular chamber between the walls 10 and 13, and into the distributing tube 14. Thus, the heated air is introduced into the innermost 45 portion of the material and is also applied to the material entirely thereabout, so as to drive out the cold air, and thoroughly permeate the material with the warm air from the chamber 12. The crib 10 is adapted to be filled with the grain, or other substance, and in order to ascertain the temperature at the middle portion of the crib, the tube 37 is employed.

55 In practice, it is found to be desirable to raise the temperature of the material in the crib 10 to not less than 130° F. This temperature should be evenly distributed not only in the center of the grain, or other substance, but also at the top and all through 60 the same. When this temperature is reached uniformly throughout the crib 10, the ventilating cap 18 is closed more or less to allow but a slow draft of air upwardly through the crib. This will retain the heat and it 65 should be maintained for approximately

forty-eight hours, after which time the ventilating cap 18 should be entirely closed, so as to prevent any draft through the crib 10. It is found that this treatment of the material in the crib 10 entirely destroys 70 and eliminates the weevils, and about once a month the material in the crib should be examined, and if the weevils or insects are found therein, the same heating process as above described should be carried out.

If heat is applied as grain is gathered, it will prevent weevil or mold. In the case of Kafir corn, the heads should be put into the crib and dried, then taken out, threshed, sacked and put back into the crib. This 80 crib may also be used for drying fruit or raisins.

The crib 10 may be utilized for storing the grain and it is only necessary to fire the furnace 24, and adjust the conducting 85 pipe 32, or the disk 34, in place to obtain the desired results and the necessary application of the heat, to evenly raise the temperature throughout the contents of the crib. Access to the heating chamber 12 may be 90 obtained through a door 41, or the like, placed in one side of the wall of the chamber, and any suitable means other than the openings 26 may be employed at the lower end of the flue 25 for introducing air into 95 the flue and upwardly through the furnace.

It is obvious that the above described structure may be modified to suit various materials, and to adapt the heater to various other uses, such as for the purpose of killing 100 moths.

What is claimed is:—

1. In a device as specified, a crib comprising a bottom adapted to contain a quantity of material to be stored and having an 105 annual chamber surrounding the same opening through the bottom of the crib and provided with an inner wall perforated substantially from the top to the bottom, and means for directing hot air into said annular chamber.

2. In a device as specified, a crib adapted to contain a quantity of material to be stored and having an annular chamber opening through the bottom of the crib and provided 115 with a perforated inner wall, a hot air conducting pipe adjustably mounted beneath the crib to distribute hot air to said annular chamber at various points thereof, and means for supplying heated air to said pipe. 120

3. In a device as specified, a crib comprising cylindrical inner and outer walls, spaced apart and connected at the top thereof forming an annular chamber closed at the top and open at the bottom, said inner wall 125 being perforated, a heating chamber beneath the crib, a vertical hot air flue centrally arranged in said heating chamber and having an opening at its upper end, and a horizontally extending conducting pipe 130

hinged at one end upon said upper end of the flue, having its opposite end arranged beneath said chamber and adapted to be swung to allow heated air to pass into the 5 annular chamber at various points around its periphery.

4. In a device of the character described, a crib comprising a bottom adapted to contain a quantity of material to be stored and 10 provided with a tube extending upwardly through said bottom into the crib spaced from the wall thereof and having perforations in its sides, heating means beneath the bottom of said crib and means separate 15 from said tube for conveying away the smoke and products of combustion.

5. In a device as specified, a crib having a bottom adapted to contain a quantity of material to be stored and having an annular 20 air chamber opening through the bottom of the crib and provided with a perforated inner wall, a tube extending upwardly through said bottom into the crib and having perforations in its sides, and heating 25 means beneath the bottom of said crib for directing heat through said opening into said annular chamber and into said tube.

6. In a device as specified, a crib adapted 30 to receive a quantity of material to be stored, a heating chamber beneath the crib, a tube projecting centrally upward into the crib and having communication with said heating chamber and being provided with perforations in its lateral walls, a second 35 perforated tube of reduced diameter supported on and rising from the top of the first tube into the upper end of the crib and being open at its upper end, and means for suspending a thermometer in said second 40 tube to ascertain the temperature of the crib at the middle of the stored material.

7. In a device as specified, a crib adapted 45 to receive a quantity of material to be stored, a heating chamber beneath the crib, a furnace in the heating chamber, a flue in the furnace projecting upwardly from the same, a hood arranged in spaced relation over the furnace to collect heated air from about the furnace, and a conducting 50 pipe adjustably mounted over the hood and over the flue to receive the heated air from the hood and the flue and conduct the same

to the desired portion of the heating chamber.

8. In a device as specified, a crib having 55 a bottom, an inwardly spaced annular wall within said crib providing thereabout an annular chamber and having perforations therein to admit air from the annular chamber into the crib, said crib having an opening in the bottom to admit air upwardly through said annular chamber and into the crib, an upwardly projecting tube mounted upon the central portion of the bottom of the crib and opening at its lower end 60 through said bottom and having perforations in its sides opening into the central portion of the crib, and heating means beneath said bottom.

9. In a device as specified, a crib adapted 70 to contain a quantity of material to be stored, means for heating the material in said crib, a tube extending from the top of the crib downwardly into the central portion thereof and adapted to be emersed in 75 the central portion of the material in the crib, said tube having perforations therein to receive the heated air from the surrounding material, and means for suspending a thermometer in the lower end of the tube 80 to obtain the temperature of the central portion of the material.

10. In combination with a crib, an air flue arranged vertically and centrally beneath the crib, a furnace surrounding the air flue, 85 a hood arranged in spaced relation over the furnace and surrounding the upper end of the air flue and adapted to collect the heated air surrounding the furnace, said flue having perforations therein at a point within 90 the hood to permit air from the hood to pass into the flue, and detachable and interchangeable air distributing devices adapted to be mounted on the upper end of the flue to receive heated air therefrom and from 95 the hood and distribute the air against the bottom of the crib.

In testimony, that I claim the foregoing as my own, I have hereto affixed my signature in the presence of two witnesses.

JOHN KASMEIER.
